CLAIM

The ornamental design for a support for a truck shell gas prop and the like, as shown and described.

DESCRIPTION

FIG. 1 is a right side elevation view of a support for truck shell gas prop showing my new design, the opposite side being a mirror image.

FIG. 2 is a front elevation view of my new design.

FIG. 3 is rear elevation view of my new design.

FIG. 4 is a top plan view of my new design.

FIG. 5 is a bottom plan view of my new design.

FIG. 6 is front perspective view of my new design; and,

FIG. 7 is a right side top perspective view of my new design.
